PAINT-SPRAYER ATTACHMENT FOR A VACUUM CLEANER

Edwin W. Vose, Orange, N.J., and Russell A. Burton,
Sturbridge, Mass., assignors to Spray Process Co. Inc.,
Orange, N.J., a corporation of New York

Filed Jan. 17, 1961, Ser. No. 63,583

Term of patent 3½ years

(Cl. D62—2)

FIG. 5

FIG. 4

FIG. 3

FIG. 1 is a view in perspective showing a paint-sprayer attachment for a vacuum cleaner, showing our new design and looking from the front above and to one side;

FIG. 2 is a view in perspective looking from the rear below and at the opposite side from FIG. 1;

FIG. 3 is a side elevation thereof;

FIG. 4 is a front elevation thereof; and

FIG. 5 is a top plan view thereof.

The paint container shown in broken lines in FIGS. 1, 2, 3 and 4 is included for illustrative purposes only.

We claim:

The ornamental design for a paint-sprayer attachment for a vacuum cleaner, as shown and described.
